UNITED STATES PATENT OFFICE.

RICHARD E. KRAUSE, OF NEW YORK, N. Y., ASSIGNOR OF ONE-HALF TO ERNEST J. KALTENBACH, OF BROOKLYN, NEW YORK.

ROTARY ENGINE.

No. 863,727.

Specification of Letters Patent.

Patented Aug. 20, 1907.

Application filed November 10, 1906. Serial No. 342,916.

To all whom it may concern:

Be it known that I, RICHARD E. KRAUSE, a subject of the King of Sweden, and a resident of the borough of Brooklyn, county of Kings, city and State of New York, have invented certain new and useful Improvements in Rotary Engines, of which the following is a specification.

An engine embodying my improvements is illustrated by the accompanying drawings, in which

10 Figure 1 is an end elevation of the engine, with some parts broken away and others in section; Fig. 2 is a plan view of the engine, with parts broken away and others in section; Fig. 3 is a vertical section on line 3—3 of Fig. 1; Fig. 4 is an end elevation showing a slightly different arrangement of certain engine parts; Fig. 5 is an inside face view of one of the end plates of the engine; Fig. 6 is a face view of one of the cylindrical rings forming part of the engine casing; Fig. 7 is a face view of a partition forming a midplate in said casing; 20 Fig. 8 is a face view of the cylindrical ring on the other side of the midplate; Fig. 9 is an inside face view of the other end plate; Fig. 10 is a face view of one of the packing strips employed on the end faces of the piston; Figs. 11 and 12 are cross-sections on lines 11—11 and 25 12—12 respectively of Fig. 10; Fig. 13 is a partial elevation of the three connected packing strips applied to the piston, and Fig. 14 is a perspective view of that portion of one of the cylindrical rings through which the abutment passes.

30 The engine shown in the drawings comprises a casing of a general cylindrical shape, divided into two chambers by a central partition parallel with the ends or covers. In detail, the end plates A, a and the midplate or partition B are shown provided with peripheral shoulders 35 against which are fitted cylindrical rings C, c, all of these parts having holes A', a', B', C', c' respectively for the passage of bolts D which with the aid of nuts D' hold the said parts together. At diametrically opposite points, the end plates are provided with extensions 40 A², a², and at corresponding points the partition B and the rings C, c have similar extensions B², C², c², respectively. One of the end plates, A (an inside view of which is shown in Fig. 5) is provided on its outside with a cover plate E, suitably fashioned to form with 45 the end plate a chamber F into which the compressed air, steam, or other driving medium is admitted through a pipe G. From the chamber F, the driving medium passes either to a port H or a port H', according to the position of a valve J contained in said chamber and 50 pressed against its seat by the driving medium. This valve has a radial stem J' suitably guided, and pressed inward by a spring K against a cam L' upon the shaft L which is journaled in the end plates A, a, the mid-

plate B, and the cover plate E. Suitable packings M, m and stuffing box covers, N n are preferably provided 55 where the shaft leaves the casing.

The port H communicates with two channels A³, A⁴ arranged in the end plate A and leading to cross passages A⁵, A⁶ respectively, which communicate with admission ports C³, C⁴ respectively formed as grooves 60 or slots in the ring extensions C² at diametrically opposite points and each arranged to discharge the driving medium into the compartment situated between the end plate A and the midplate B. (In Figs. 6 to 9 the several parts have been shown in the same position 65 which they occupy when assembled, but the end plate A is shown reversed in Fig. 5, that is, the part shown at the left of Fig. 5 fits on the part shown at the right of Fig. 6.) The port H' communicates with a channel A⁷ in the end plate A, the orifice of said channel registering with passages C⁵, B³ and c⁵ of the ring C, midplate B, and ring c respectively. The passage c⁵ communicates with an orifice a⁷ in the end plate a, from which two channels a³, a⁴ lead to cross-passages a⁵, a⁶, respectively, communicating with admission ports 70 C³, C⁴ respectively. These ports are formed as grooves or slots in the ring extensions C² at diametrically opposite points, preferably in exactly the same positions as the ports C³, C⁴ as will be seen by comparing Fig. 6 with Fig. 8. Thus it will be understood that according to the position of the valve J, the driving medium will be admitted at diametrically opposite points, to one or the other of the compartments separated by the midplate B. The driving fluid is allowed to escape, after performing its work, through exhaust ports C⁸, C', 85 c⁸, c' respectively formed as grooves or slots in the ring extensions C², c² respectively, at diametrically opposite points which are at a slight distance from the admission ports C³, C⁴, c³, c⁴ respectively.

Between the inlets C³, C⁴, c³, c⁴ and the adjacent outlets C⁶, C⁷, c⁶, c⁷ respectively, the ring extensions C², c² are provided with guide slots C⁸, c⁸ respectively, the width of which is equal to the distance between the opposing faces of the end plates A, a and the midplate B, as shown in Fig. 2. In the slotted faces of the 90 extensions C², c², are fitted and bolted or otherwise secured caps Q which also fit tightly on the end plates A, a and on the midplate B. These caps are formed with guides registering with the slots C⁸, c⁸, and in said slots and guides are adapted to move the sliding 95 abutments, the inner ends of which project into the chambers of the casing, to engage the pistons L² secured to the shaft L. Each piston is provided with a plurality of radial or approximately radial shoulders L³, at the outer ends of which the piston engages the 100 inner peripheral surface of the ring C or c. The 105

greater portion of the piston's periphery is cylindrical, and there is a gradual transition from the cylindrical portion to the outer ends of the steps or shoulders L^3 .

Each of the abutments consists of two sections O and O' respectively, which have a sliding connection with each other, and preferably a telescoping construction is employed, as shown in Fig. 1, where the section O' is forked to receive the section O , and a pin-and-slot connection O^2 permits a limited movement of the inner section O relatively to the outer section O' . A plug O^3 , screwing into the section O' , serves as an abutment for the outer end of a spring P which forces the section O inward. This plug is also engaged by a spring R contained in the cap Q and forcing the entire abutment inward. A plug Q' screwing into the cap Q engages the outer end of the spring R . To check the outward movement of the abutment I employ a buffer of any suitable construction, for instance a spring S interposed between the plugs O^3 and Q' and so short that it will not be compressed until the abutment reaches its outermost position as shown at the top in Fig. 2. A groove O^4 may be provided in that surface of the abutment section O which is in engagement with the piston L^2 .

In order to secure a tight joint between the piston and the casing, I provide self-adjusting packing strips of a peculiar construction and arrangement on the end plates A , a , the midplate B , and the piston L^2 . The packing strips on the piston are arranged at points of its greatest diameter, and comprise at each point two strips on the end faces of the piston and a connecting strip on the periphery of the piston. For the convenience of manufacture and insertion, the base of each of the side strips T may be rectangular, but the packing strip itself, that is the portion adapted to engage the end plate A or a or the midplate B , tapers toward the shaft L , as shown at T' . These side strips T are fitted into suitable grooves of the piston L^2 (see Fig. 3) and their ends fit into grooves or sockets in the shaft L . The outer ends of the side strips T , T' are reduced, as shown at T^3 , for connection with the forked ends U^3 of the cross strip U having a rib U' to engage the inner periphery of the ring C or c . The strips are held together by pins extending through the forks U^3 and reduced ends T^3 , with sufficient play to allow the side strips T , T' to move from each other and the cross strip U to move outward, under the influence of springs V set in pockets of the piston. The ribs T' , U' are preferably rounded (Figs. 11 and 12) at that edge which is forward during rotation. Preferably, they are also provided with longitudinal grooves, T^2 , U^2 to retain lubricant.

Packing strips t similar to the strips T and pressed by springs v are located in radial grooves A^8 , B^4 , a^8 arranged in the end plate A , midplate B and end plate a respectively, in line with the center of each abutment. The strips t correspond exactly to the showing in Figs. 10, 11 and 12, except that the reduced extension T^3 is omitted. They are also shorter, so as not to interfere with the inward movement of the abutment, (see Fig. 2, especially the lower half thereof.) The rounded edges of the strips t face rearward, so that during the rotation of the piston, the rounded edges of the strips T , t will come together first, allowing the piston strips T to slide easily over the stationary strips t . As these

strips taper inwardly, having radial edges, they will engage with and leave each other at the same moment over their entire length.

The steps or shoulders L^3 of the pistons on opposite sides of the midplate B are staggered, as indicated in Figs. 2 and 3, so that the engine is self-starting in any position; that is, there is a difference of 90° between the positions of the steps or shoulders L^3 on opposite sides of the midplate B .

In operation, the air, steam or other driving medium enters at G into the chamber F , and according to the position of the valve J passes to one side of the midplate B or the other, reaching the admission ports C^3 , C^4 or c^3 , c^4 respectively. The same set of ports remain open for a quarter of a revolution at a time, and then the position of the valve J is changed by the cam L' , and the driving medium passes to the other half of the engine, on the opposite side of the midplate B . The driving medium fills the space between the abutments and the shoulders L^3 of the active piston, at diametrically opposite points, so that one-sided strains are avoided. The springs P , R keep the abutment against the periphery of the piston. Packing strips of the character described might be provided on sides of the abutment to engage the midplate and end plates, but I believe that in practice this will not be necessary. The rotary parts, however, which are subject to much greater wear, require very efficient and self-adjusting packing. The cross strips U will prevent the escape of steam along the piston's periphery, and the side strips, T , T' will prevent any leakage between the flat faces of the piston and the end plate or midplate, adjacent to the steps or shoulders L^3 . Similarly, the self-adjusting spring-pressed packing strips t , in line with the abutments, will hug the flat faces of the piston tightly, so that no escape of driving medium is possible from what may be termed the working chamber, that is, the sector bounded by two radii drawn respectively through an abutment and the packing strip U which at the time is in operative relation to said abutment. The rounding of those edges of the strips T , t which are adapted to engage each other first, insures an easy passage of the rotary strips over the stationary ones. The engine, therefore, has and preserves tight joints, and consequently its efficiency does not diminish owing to leakage due to wear. The construction of the abutment in two sections having a spring connection relieves the abutment of jars during the inward movement, that is, when the abutment suddenly jumps the distance of the step or shoulder L . This construction also prevents the repeated impact of the abutment from wearing a groove into the piston surface, since the shock is taken up successively by the springs P , R and is therefore much lighter. Similarly, as the abutment is raised, or moved away from the center, by the rotation of the piston, the shock is avoided or deadened by the successive action of the springs P and R and of the buffer constituted by the spring S or otherwise constructed. The abutment is somewhat wider than the piston, and the end plates A , a , and midplate B have guide grooves for the abutment.

In Fig. 1 the position of the port A^7 and of the valve J is just 90° from the positions of the two abutments, and corresponding positions of the ports B^3 , C^5 , c^5 , a^7 , have been shown in Figs. 3 and 5 to 9 inclusive. This arrangement presents the slight drawback that the dis-

tance from the port H to the port A⁵ is a little greater than that to the port A⁶, and the same thing is true of the relative distances from the port H' to the ports a⁵, a⁶ (see Figs. 5 and 9). The operation might therefore be 5 slightly uneven owing to an uneven distribution of the driving medium. In order that the paths from the ports H, H' to the respective ports A⁵ and A⁶ or a⁵ and a⁶ may be of exactly the same length (thus avoiding the uneven action above referred to) it is sufficient to adopt 10 the slightly different arrangement shown in Fig. 4, where the port A⁷ and the ports H, H' lie a little to one side, on a perpendicular drawn through the center to a diameter connecting the centers of the ports A⁵, A⁶. The valve J, and ports B³, C⁵, c⁵ and a⁷ would of course 15 be shifted accordingly.

This re-arrangement, and other changes may be made without departing from the nature of my invention as defined in the appended claims.

I claim as my invention

20 1. A rotary engine comprising a cylindrical casing having an inlet and an outlet for the driving medium, and provided with end plates, elastic packing strips extending inward on said plates adjacent to the inlet, a rotary piston in said casing, elastic packing strips extending inward on 25 the end faces of the piston, and a sliding abutment adjacent to said inlet.

2. A rotary engine comprising a cylindrical casing having an inlet and an outlet for the driving medium, and provided with end plates, elastic packing strips extending 30 radially on said plates adjacent to the inlet and tapering toward the center of the casing, a rotary piston in said casing, elastic packing strips extending radially on the end faces of the piston and tapering toward the piston's axis, and a sliding abutment adjacent to said inlet and in engagement 35 with the piston's periphery.

3. A rotary engine comprising a cylindrical casing having an inlet and an outlet for the driving medium, and provided with end plates, elastic packing strips extending inward on said plates adjacent to the inlet, a rotary piston 40 in said casing, elastic packing strips extending inward on the end faces of the piston, the said packing strips having longitudinal grooves in their operative surfaces, and a sliding abutment adjacent to the inlet and in engagement with the piston.

45 4. A rotary engine comprising a cylindrical casing having an inlet and an outlet for the driving medium, and provided with end plates, elastic packing strips extending radially on said plates adjacent to the inlet and tapering toward the center of the casing, a rotary piston in said 50 casing, elastic packing strips extending radially on the end faces of the piston and tapering toward the piston's axis, all of the said packing strips having longitudinal grooves in their operative surfaces, and a sliding abutment engaging the piston adjacent to the inlet.

55 5. A rotary engine comprising a cylindrical casing having an inlet and an outlet for the driving medium, and provided with end plates, a rotary piston in the casing, a sliding abutment engaging the piston, spring-pressed packing strips extending radially on said end plates, spring-pressed packing strips extending radially on both end faces of the piston, and a spring-pressed packing strip arranged transversely on the periphery of the piston and in engagement with the cylindrical inner wall of the casing.

60 6. A rotary engine comprising a cylindrical casing having an inlet and an outlet for the driving medium, and provided with end plates, a rotary piston in the casing, a sliding abutment engaging the piston, spring-pressed packing strips extending radially on said end plates, spring-pressed packing strips extending radially on both end faces of the piston, and a spring-pressed packing strip arranged transversely on the periphery of the piston and in engagement with the cylindrical inner wall of the casing, the said radial packing strips being rounded along those edges which are adapted to engage each other first during the 70 rotation of the piston, to allow them to pass over each other smoothly.

7. A rotary engine comprising a casing having an inlet and an outlet for the driving medium, and provided with end plates, a rotary member arranged in the casing, spring-pressed packing strips extending radially on the end faces 80 of said member at corresponding points and engaging the end plates of the casing, and a spring-pressed transverse packing strip extending from one of said radial strips to the other and connected therewith so that the three strips may be applied and removed together, the connection 85 being a loose one so as to allow each of the connected strips to move independently within certain limits, said transverse packing strip being arranged on the periphery of the rotary member and in engagement with the cylindrical inner wall of the casing. 90

8. A rotary engine comprising a cylindrical casing having an inlet and an outlet for the driving medium, and provided with end plates, a rotary piston in the casing, a sliding abutment engaging the piston, spring-pressed packing strips extending radially on said end plates, spring-pressed packing strips extending radially on both end faces 95 of the piston, and a spring-pressed packing strip arranged transversely on the periphery of the piston and in engagement with the cylindrical inner wall of the casing, the said radial packing strips tapering toward the axis, on their operative surfaces.

9. A rotary engine comprising a cylindrical casing having an inlet and an outlet for the driving medium, and provided with end plates, a rotary piston in the casing, a sliding abutment engaging the piston, spring-pressed packing strips extending radially on said end plates, spring-pressed packing strips extending radially on both end faces of the piston, and a spring-pressed packing strip arranged transversely on the periphery of the piston and in engagement with the cylindrical inner wall of the casing, the said 105 radial packing strips having longitudinal grooves in their operating surfaces.

10. A rotary engine comprising a cylindrical casing having an inlet and an outlet for the driving medium, and provided with end plates, elastic packing strips extending 115 inward on said plates adjacent to the inlet, a rotary piston in the casing, elastic packing strips extending inward on the end faces of the piston, the meeting edges of the said casing strips and piston strips being rounded to allow them to pass over each other smoothly, and a sliding abutment arranged to engage the piston adjacent to said inlet.

11. A rotary engine comprising a casing with a partition dividing it into two compartments, an inlet chamber having separate connections with said compartments, rotary members in said compartments, a shaft on which both members are secured, a valve mounted to slide radially toward and from said shaft, for connecting the inlet chamber with said compartments alternately, and means for operating the valve from the shaft directly. 125

12. A rotary engine comprising a casing provided with an inlet and an outlet, a rotary member in said casing, an abutment arranged to slide in the casing between the inlet and the outlet, said abutment consisting of an inner member and an outer member having a limited sliding movement relatively to each other, a spring for pressing the inner member inward relatively to the outer member, another spring for pressing the outer member and the inner member toward the rotary member, and a buffer for checking the outward movement of the outer abutment member. 130

13. A rotary engine comprising a casing provided with an inlet and an outlet, a rotary member in said casing, an abutment arranged to slide in the casing between the inlet and the outlet, said abutment consisting of telescoping members, means having a tendency to separate said abutment members, means for pressing the abutment against the periphery of the rotary member, and a buffer for checking the outward movement of the abutment. 135

In testimony whereof I have hereunto signed my name in the presence of two subscribing witnesses.
